UNITED STATES PATENT OFFICE.

ADOLPH T. PRAECKEL, OF NEW YORK, N. Y.

MOUTH AND NOSE GUARD FOR FIREMEN.

SPECIFICATION forming part of Letters Patent No. 601,401, dated March 29, 1898.

Application filed July 10, 1897. Serial No. 644,157. (Model.)

To all whom it may concern:

Be it known that I, ADOLPH T. PRAECKEL, a citizen of the United States, and a resident of New York, in the county of New York and State of New York, have invented certain new and useful Improvements in Mouth and Nose Guards for Firemen, &c., of which the following is a specification.

My invention relates to a mouth and nose guard for firemen, miners, and others in apartments or mines filled with smoke, foul air, or obnoxious gases; and it consists of the novel construction, as hereinafter more particularly described, illustrated in the accompanying drawings, and pointed out in the claim.

Referring to the accompanying drawings, Figure 1 represents a front view of a mouth and nose guard, part of the sponge omitted, embodying my invention. Fig. 2 represents a partial side view and partial section thereof. Fig. 3 represents a top view thereof. Fig. 4 represents a rear view thereof.

Similar letters of reference indicate corresponding parts.

The letter A indicates a metallic frame approximately of the shape of the human mouth, having a curved back piece B to fit over the mouth, and the letter C designates wire-gauze arranged in back piece opposite the mouth portion.

The letters D and D' designate overhanging lips on the front of the guard and having a piece of sponge E or other suitable material fitted between the said overhanging lips

D and D' and secured in place therein by

spring-clamps a a' a'', hinged to the lower lip.

In the upper overhanging lip opposite the nose I place an opening F to permit breathing through the nostrils.

On the rear of the frame and on each side of the wire-gauze I arrange protecting-cushions G, composed of compressed sponge H and inclosed in a covering I, it being ap-

proximately the shape of the mouth and to fit snugly thereto.

The letter J designates a piece of sheet-rubber or other suitable material secured to the outside of the frame A on the upper side thereof by first sewing the same and then applying a suitable adhesive substance thereto, thus making an air-tight connection of the sheet-rubber to the frame. The upper part of the sheet-rubber is shaped to fit the lower portion of the nose, and in order to make the rubber hold and close in an air-tight manner around the nose I attach springs L L to the upper lip and provide the springs with pressure-pads M M, the rubber piece J having reinforcing-cushions N N thereon opposite the pressure-pads M M, the pressure-pads M M serving to hold the guard in its proper position by pressing the bone of the nose.

In order to protect the pressure-pads M M, I inclose them in a pocket P' in such a manner as to permit a slight lateral movement of the pads in said pockets. In that case the reinforcing-cushions N N are dispensed with.

In order to secure the device on the mouth and nose, I attach loops O O to each side of the frame and place straps P therein.

What I claim as new, and desire to secure by Letters Patent, is—

A mouth and nose guard consisting of an open frame, fitting around the mouth, covered with wire-gauze in front of which is a casing for carrying a sponge, to the top of said casing is attached a sheet-rubber flap held to cover the nose by spring-support pads, and having suspending straps for securing the structure, substantially as shown and described.

ADOLPH T. PRAECKEL.
